(57) **CLAIM**

The ornamental design for a pull tab, as shown and described.

DESCRIPTION

FIG. 1 is a perspective view of a pull tab for zipper;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view, wherein the pull tab is connected to a zipper by applying the rope member.

It being understood that the broken lines in FIG. 8 are for exemplary illustrative purposes only and form no part of the claimed design.
